UNITED STATES PATENT OFFICE.

ALFRED J. GILLESPIE, OF ROCHESTER, NEW YORK, ASSIGNOR TO THE STANDARD VOTING MACHINE COMPANY, OF SAME PLACE.

DESIGN FOR A MACHINE-LEG.

SPECIFICATION forming part of Design No. 32,510, dated April 10, 1900.

Application filed March 12, 1900. Serial No. 8,411. Term of patent 14 years.

To all whom it may concern:

Be it known that I, ALFRED J. GILLESPIE, of Rochester, in the county of Monroe and State of New York, have invented and produced a new and original Design for a Machine-Leg, of which the following is a specification, reference being had to the accompanying drawings, in which—

Figure 1 is a perspective view of a machine-leg, showing my design; and Fig. 2, a front view thereof.

The leg embodies the lower portions A A,

curving gradually toward each other from the bottom to the top, where they are connected by the curved portion B, and a brace C extends between the portions A, as shown.

I claim—

The design for a machine-leg substantially as herein shown and described.

ALFRED J. GILLESPIE.
